UNITED STATES PATENT OFFICE.

JAMES GUTHRIE, OF ELYRIA, AND JOHN W. SIMMONS, OF CLEVELAND, OHIO; SAID GUTHRIE ASSIGNOR TO THE SIMMONS MANUFACTURING COMPANY, OF CLEVELAND, OHIO, A CORPORATION OF OHIO.

RHEOSTAT.

Application filed August 4, 1922. Serial No. 579,598.

To all whom it may concern:

Be it known that we, (1) JAMES GUTHRIE and (2) JOHN W. SIMMONS, citizens of the United States, residing at (1) Elyria, and (2) Cleveland, in the county of (1) Lorain, and (2) Cuyahoga, and State of Ohio, have invented a certain new and useful Improvement in Rheostats, of which the following is a full, clear, and exact description, reference 10 being had to the accompanying drawings.

This invention is a novel construction of rheostat or resistance device particularly adapted for use in connection with radio apparatus, although it will be understood that 15 the device or the principle thereof can be used for other purposes.

The object of the invention is to provide an exceedingly cheap and simple construction of rheostat involving a resistance pile of 20 carbon disks and a still further object is to provide a novel form of resistance pile and also a novel means of adjusting or regulating the resistance with ease and accuracy. With these various objects in view the invention 25 consists in the novel features of construction and in the manner of combining or arranging the same, all of which will be fully described hereinafter and pointed out in the claims.

30 In the drawings forming a part of this specification Fig. 1 is a side elevation partly in section, illustrating a rheostat constructed in accordance with our invention; Fig. 2 is a top plan view of the same; Fig. 3 is a transverse vertical section; Fig. 4 is a horizontal section on the line 4—4 of Fig. 1; and Fig. 5 is a diagram of a curve indicating 35 variations in resistance due to movement of actuating means.

40 In the practical embodiment of the invention there is employed a container or receptacle 10 preferably cylindrical in form and made of porcelain or other suitable material. The bottom of this receptacle has a central aperture 11 through which is passed the binding post 12 having the nuts 13 arranged thereon and the head of this binding post is 45 preferably countersunk into a disk 14 of any suitable material. The upper end of the

cylindrical container is formed with a laterally projecting flange 15 which is preferably square or rectangular in shape as indicated in Fig. 2. Within the cylindrical porcelain container we arrange a resistance pile composed of alternate layers of perforate and imperforate carbon disks 16 and 17, respectively, these disks being quite thin and by making every other disk with a central opening as indicated at 16^a we are able to produce a pile composed of thin disks and which will 50 not tend to warp or get out of place; and by maintaining perfect contact between the series of disks, provide a better resistance element. Bearing upon the resistance pile of carbon disks is a plunger 18 having the lower 55 end 18^a and a coil spring 19 which surrounds the plunger and bears upon this enlarged lower end exerts a constant downward pressure upon the plunger and resistance pile, this spring bearing at its upper end 60 upon a plate 20 which is rigidly connected to the top of the porcelain container by means of screws 20^a, said plate having a central aperture through which the upper end 65 of the plunger passes as most clearly shown 65 in Fig. 3. The plate 20 is formed with upwardly projecting flanges or wings 21 at the opposite ends thereof and working through these flanges is a rotary shaft 22 having a hand wheel 23 upon the outer end thereof. 70 By means of the forward flange the device 75 can be rigidly connected to a portion 24 of the casing or panel which is preferably formed of some dielectric material. The shaft 22 has its inner end journaled in the inner flange or wing 21 and is threaded as shown at 25 and carries thereon a block 26 80 having a threaded hub portion 27. The bottom portion of this block is apertured or recessed as shown at 28, in order that said 85 block may move back and forth upon the plate 20 and straddle the upwardly projecting end of the plunger rod. An actuating lever in the form of a bail is connected to the upper end of the plunger rod and in turn 90 bears with its upper end against the rear face of the block 26. This lever is indicated 95 at 30 and it will be noted that the lever com-

prises parallel members and a connecting member at the top. The lower ends are turned inwardly into engagement with the upper end of the plunger rod. The parallel members are curved on the arc of a circle and at their upper ends where they meet the connecting portion they are turned radially outwardly. By having this actuating lever curved on the arc of a circle and actuating the same by means of the block 26 which moves rearwardly, the lever fulcrums upon the plate 20 and lifts the plunger rod against the compression spring 19. In making this movement the lever is constantly shifting its fulcrum point, or in other words, the curved portion of the lever is rolling upon the flat plate and in this manner the variation in resistance is very gradual at first and increases in a variable manner as most clearly shown by the diagram of Fig. 5, the curved line indicating by its upper end the condition of least resistance and the lower end of the curved line indicating the condition of greatest resistance. It will be noted that the variation for the first and second stage starting from the lower left hand corner, is very great and during the successive stages decreases according to a predetermined ratio. When the pile is compressed as shown in Figs. 1 and 3 the resistance is least and when pressure is relieved the resistance increases according to the same curve. By means of the arc shaped lever and the laterally movable block actuated by the shaft 22, we are able to obtain exceedingly fine and accurate variations in the resistance pile.

It will be understood that the lever bail 30 is formed of a good variety of wire which has some resiliency and consequently that in connection with the compression spring 19 will maintain the actuating lever 30 constantly in engagement with the movable block 26 while within its range of travel. A binding post 40 may be connected to the rear flange 21 at any desired point. The resistance pile, of course, contacts with the disk 14 at the bottom of the container and also with the enlargement 18^a at the lower end of the plunger rod.

It will thus be seen that there is provided an exceedingly simple and inexpensive form of rheostat which will provide a maximum or minimum amount of resistance for a given size of article and it will also be noted that the very finest variations of the resistance can be quickly, easily and accurately effected.

Furthermore by completely moving the plunger out of contact the circuit will be opened. If desired all the disks can be perforated. By using perforated disks line contacts between disks is prevented in case of warping of the disk, and disks of larger diameter can be employed increasing the resistance variations.

The form of lever bail can also be varied if desired to obtain any ratio of increase or decrease desired.

Having thus described our invention, what we claim is:

1. In a rheostat, a resistance pile composed of alternate perforated and imperforated resistance disks.
2. In a rheostat, a resistance pile composed of resistance disks, means for containing the same, means for normally exerting pressure thereon, and means for varying said pressure according to a predetermined ratio.
3. In a rheostat, a resistance pile composed of alternate perforated and imperforated resistance disks, and a container for the same, a plunger bearing upon said pile with a normal uniform pressure, and means for relieving said pressure with a gradual increasing variation.
4. In a rheostat, a resistance pile composed of a series of resistance disks and a container for the same, a plunger bearing upon said pile with a normal definite pressure, a lever connected to one end of said plunger and a laterally movable member adapted to engage said lever for the purpose of moving said plunger.
5. In a rheostat, a resistance pile composed of a series of alternate perforated and imperforated resistance disks and a container for the same, a plunger bearing upon said pile with a normal definite pressure, a lever connected at one end to said plunger and a laterally movable member adapted to engage said lever for the purpose of moving said plunger.
6. In a rheostat, a container, a series of resistance units arranged therein, a plunger resting upon said resistance units within the container, a flanged plate secured to the top of said container, said plate having an opening through which the end of the plunger projects, a pressure exerting member actuating said plunger and exerting pressure against said plate and resistance units, a lever connected at one end to said plunger and fulcruming upon said plate, a laterally movable member and means for actuating the same, said member contacting with the free end of said lever and causing the same to move the plunger and increase or decrease the pressure upon the resistance pile.
7. In a rheostat, a container, a series of resistance units arranged therein, a plunger resting upon said resistance units, a plate secured to the top of said container, said plate having an opening through which one end of the plunger projects, a pressure exerting member acting upon said plunger, a lifting member connected to the plunger and bearing upon the plate and means carried by the plate for actuating said lifting member.
8. In a rheostat, a container, a series of

resistance units arranged therein, a plunger resting upon said resistance units, a plate secured to the top of container and having an opening through which the end of plunger projects, a curved lever connected to said plunger, said lever bearing upon the plate, a laterally movable member engaging the

free end of said lever, and means for moving said member.

In testimony whereof, we hereunto affix 10 our signatures.

JAMES GUTHRIE.
JOHN W. SIMMONS.
